Alfred E. Dunn

ATTORNEY

UNITED STATES PATENT OFFICE.

ARCHIE OAKES, OF DETROIT, MICHIGAN, ASSIGNOR TO SQUARE D COMPANY, OF DETROIT, MICHIGAN, A CORPORATION OF MICHIGAN.

OUTSIDE LOCK-OFF AND CENTER STOP FOR ELECTRICAL SWITCHES.

1,387,558.

Specification of Letters Patent.

Patented July 5, 1921.

Application filed June 13, 1918. Serial No. 239,724.

To all whom it may concern:

Be it known that I, ARCHIE OAKES, a citizen of the United States, residing at Detroit, in the county of Wayne and State of Michigan, have invented certain new and useful Improvements in Outside Lock-Offs and Center Stops for Electrical Switches, of which the following, taken in connection with the accompanying drawings, form a complete and exact description thereof.

My invention relates to outside lock off and center stop devices for electrical switches of the inclosed type.

An object of my invention is to provide a lock off which may be attached to the exterior of the casing of an inclosed switch.

A further object of my invention is to provide a center stop device which is adapted to temporarily retain a double throw switch in neutral position.

A further object of my invention is to provide a device of the above type which permits only a rapid motion from one extreme position to the other extreme position of a double throw switch.

A further object of my invention is to provide a construction whereby when the switch is temporarily held in neutral position, it may be manually released.

A further object of this invention is to generally simplify the construction of outside lock offs for electrical switches.

A further object of this invention is to incorporate in one structure devices which permit the locking off of the switch and also one which permits only a rapid motion of the switch from one extreme position to the other and further may be used to temporarily retain the switch in neutral position.

One of the many possible forms of the invention is shown in the accompanying drawings, in which—

Figure 1 represents a side elevation of an inclosed switch (in dotted lines), and the outside lock off mechanism.

Fig. 2 is a plan view of the device; and

Fig. 3 is a side elevation thereof.

This device consists of a horizontal plate 1 which is provided with a flange 2 which is

adapted to be attached to the outside of the casing 3 of an electrical switch of the double throw type. This switch mechanism is not shown in detail in the drawing, but only so much thereof as coöperates with this lock- 55 ing and center stop mechanism.

Referring now to Fig. 2, it will be seen that the plate 1 is provided with slots 4 adjacent each end thereof, said slots guiding headed pins 5. A second plate, which is 60 movably retained in position by means of the slots 4 and headed pins 5, is indicated at 6, and is provided with inclined edges 7 symmetrically arranged on either side of a central notch 8. A spring 9 has its ends 10 passing through ears 11 formed integrally with the plate 1. The central part of the spring 9 passes around a stud 12 located in the plate 6, and is adapted to transmit its outward pressure centrally of the plate 6 through the 70 medium of this stud 12, thereby holding the headed pins 5 in engagement with the outer ends of the slots 4. A finger piece 13 is provided upon the plate 6 whereby said plate may be pressed inwardly out of its operative 75 position.

The switch with which this device is adapted to coöperate may be of the double throw type and includes an external operating member 14 which is provided with a 80 handle 15 at its upper end and is pivotally mounted in the case 3 at its lower end 16.

From a reference to Fig. 1, it will be seen that when the operating member 14 is in its central or upright position, it engages the 85 notch 8 and is thereby held in such position. This position is the neutral position of the switch.

Upon reference to Figs. 2 and 3, it will be seen that the stationary plate 1 and movable plate 6 are each provided with alining openings 17. These openings are adapted to receive the bail portion of a padlock or other locking means. It will, therefore, be understood that the operating member 14 may be 95 engaged in the notch or recess 8 and the bail portion of the padlock or other means passed through the alining openings 17 and locked, thereby permanently locking the switch in "off" position.

It is sometimes desirable to throw the double throw switch from one extreme position to the other—as, for instance, in motor starting—and it becomes necessary to prevent any but rapid motion from one extreme position to the other. This is secured by the device above described, for as the operating member 14 rides along either of the inclined faces 7 it depresses the member 6 and if the motion of the member 14 is rapid enough, the plate 6 acquires sufficient momentum to temporarily hold the notch 8 clear of the path of the operating member 14. However, if it is attempted to slowly move the operating member 14 from one extreme position to the other, the plate 6 immediately snaps outwardly and the notch 8 engages the member 14.

When it is desired to release the operating member 14 from its locked position, if a padlock is used, it is, of course, first removed and the finger piece 13 is depressed, thereby releasing the operating member 14 from engagement with the notch 8.

When the switch operating member 14 is moved from one of its extreme positions to engage with either of the inclined edges 7, it will move the plate 6 inwardly against action of an end 10 of the spring 9. This motion will be oscillatory about the pin 5 which is opposite the engaged inclined edge 7, for the end 10 will hold such pin 5 in the lower position as shown in Fig. 2, while the engagement of the operating member 14 with the inclined edge 7 forces the other pin 5 to travel in the other slot 4. As the operating member comes near the notch 8, the plate 6 will then pivot about the pin 12 so that both pins 5 will slide upwardly, as viewed in Fig. 2. When the arm 14 is moved the other way, the plate first pivots about the pin 5 which was first described as sliding in the slot 4. On account of the symmetrical mounting of the plate 6 with respect to the two arms 10 of the spring 9, it will be noted that the plate is adapted to pivot about either one of the pins 5 depending upon which way the switch operating member is moved. When the padlock is used to coöperate with the alining openings 17, the plate 6 is practically immovable for it cannot pivot about either pin 5 nor slide bodily.

From the above detailed description and from the drawings it will be seen that applicant has provided a very simple device which is possessed of a number of desirable characteristics and functions. For example, it is possible to lock the switch in "off" position; it is also possible to retain the switch temporarily in "off" position and readily release the same; and it is also further possible to insure a rapid motion from one extreme position to the other extreme position.

All of these functions, it will be noted, are secured by this one device, considered as an entirety.

It is understood, of course, that the above detailed description and drawings are to be interpreted in an illustrative sense only and the invention is not to be limited, other than as defined by the following claims:

Having thus described my invention what I claim as new and desire to secure by Letters Patent of the United States is:

1. A center stop for double throw switches comprising a fixed member, a notched movable member attached thereto, and a spring between said members, said fixed member having slots therein, and coöperating pins on said movable member.

2. A center stop for double throw switches comprising a fixed member, a notched movable member attached thereto, and a spring between said members, said fixed member having slots therein, and coöperating headed pins on said movable member.

3. A center stop for double throw switches comprising a fixed member, a notched movable member attached thereto and having an inclined edge, and a spring between said members, said fixed member having slots therein and coöperating pins on said movable member.

4. A center stop for double throw switches comprising a fixed member and a movable notched spring pressed member, a finger piece on said movable member, and means for slidably holding said members together.

5. A center stop for double throw switches comprising a fixed member and a movable notched spring pressed member, a finger piece on said movable member, and means for slidably holding said members together, comprising slots and headed pins coöperating therewith.

6. A center stop for double throw switches comprising a stationary member provided with guiding slots, a movable notched member, a spring intermediate said members attached centrally of the movable member, headed pins adjacent the ends of the movable member coöperating with said guiding slots, whereby said movable member is adapted to pivot about either end.

7. A center stop for double throw switches comprising a stationary member provided with guiding slots, a movable notched member having inclined edges, headed pins adjacent the ends of the movable member coöperating with said guiding slots, whereby said movable member is adapted to pivot about either end.

8. A center stop for double throw switches comprising a stationary member provided with guiding slots, a movable member having a central notch and symmetrical inclined edges on each side of said notch, a spring

intermediate said members and arranged to bear centrally of the movable member, headed pins adjacent the ends of the movable member co-operating with the guiding slots, 5 whereby said movable member is adapted to pivot about either end.

9. The combination with a double throw

switch of a center stop and lock off comprising a stationary plate and a movable spring pressed notched plate having alining 10 openings, said movable plate having headed pins and said stationary plate having co-operating guiding slots.

ARCHIE OAKES.
